WILLIAM K. LYNN AND WALTER T. WEAVER, OF GULFPORT, MISSISSIPPI.

LINING FOR JOURNAL-BOXES.

1,204,465.

Specification of Letters Patent. Patented Nov. 14, 1916.

Application filed April 28, 1916. Serial No. 94,222.

To all whom it may concern:

Be it known that we, WILLIAM K. LYNN and WALTER T. WEAVER, citizens of the United States, both residing at Gulfport, in the county of Harrison and State of Mississippi, have invented certain new and useful Improvements in Linings for Journal-Boxes, of which the following is a specification, reference being had therein to the accompanying drawing.

This invention relates to improvements in liners adapted for use in connection with journal boxes to take up the wear between the face of the journal-box and hub of the wheel.

The primary object of the invention is the provision of a liner possessing improved attaching means coöperating with complementary parts on the journal box for enabling ready attachment or detachment of the liner relative to its operative position between the end of the journal box and the hub of the adjacent wheel. Heretofore in this art in order to take up the wear to which we have alluded, it was originally necessary to remove or drop the wheels and associated parts, enabling the substitution of a new journal box or the fastening of a supplemental rail plate thereon, but to overcome this disadvantage many attempts have of late been made to provide a liner capable of being attached to the journal box without the expense and delay of removing any of the parts of the locomotive or vehicle, but in each instance so far as we are advised the interlocking means provided between the journal box and liner or plate has either been of a relatively loose engagement necessitating supplemental fastenings, or in wedge engagement on the end of the journal box presenting angular edges, ribs or lugs, exposed to breakage.

Our present improvement overcomes the disadvantageous characteristics just noted in that the same contemplate a liner having the whole of its outer face capable of a uniform, flat contact with the abutting face of the end of the journal box, and securing means at the sides of the journal box for wedging the liner in a fixed relation to the journal box by drawing said outer face of the liner firmly against the face of the end of the box, so that any impact or shock against the inner face of the liner is distributed over a wide area approximately co-extensive with

the size of the liner itself and from the liner to the body of the journal box.

To facilitate an understanding of the invention we will illustrate in the accompanying drawings forming part hereof the preferred embodiment of the invention, the improved details in construction and arrangement of the several parts thereof being readily understood from the specific description hereinafter contained when read in connection with said drawings.

In the drawings: Figure 1 is a top view of a journal box with our improved liner attached thereto; Fig. 2 is an inner face view of the liner in position, as indicated in Fig. 1; Fig. 3 is a side view, and, Fig. 4 is a vertical sectional view.

Referring more specifically to the drawings, A represents a journal box of conventional or other preferred type, the same having formed in the side edges thereof near the inner face of the journal box, alined oppositely disposed outwardly opening vertical grooves B. The outer walls of these grooves, indicated at C, are vertical or straight, to be parallel with the inner face or end D of the journal box, whereas the inner walls of the grooves, represented at E, incline downwardly and outwardly constituting wedging surfaces, as will be apparent.

F is the detachable liner, the same having flat inner and outer surfaces, the latter corresponding to the inner end or face D of the journal box so as to occupy parallel relation thereto and to have a flat even engagement therewith throughout the extent of the plate, the opposite vertical side edges of the liner having upwardly extending flanges G, spaced a suitable distance apart to slide vertically over the side edges of the journal box, the outer edges of the flanges terminating in inwardly turned wedge parts H, the faces J and K of which are parallel to each other but inclined downwardly and outwardly with reference to the liner F, to be complementary to and coöperate with the wedging surfaces E of the grooves in the sides of the journal box. Of course it is not necessary that the outer faces J of the wedge parts be inclined, so long as the proportions are such that there is a space L always preserved between the same and the vertical wall C of the groove B, so that no impact can take place between the wedge parts and

the wall C of the groove, which might tend to break or fracture the same under the pressure or binding encounter of working conditions.

- 5 From the foregoing description it will be understood that the liner being dropped into place from the top of the journal box with the wedge parts F traversing downwardly, the groove C, the coöperating 10 wedge surfaces E and K will draw the liner F up into an impinging relation to the end D of the journal box and constitute the whole a rigid structure capable of distributing the strains of impact or other shock 15 throughout the liner and from the liner to and throughout the journal box, as previously observed, and so without undue strains upon the securing flanges and wedge parts carried thereby.
- 20 The driving of the liner home will create sufficient friction between the opposing faces of the journal box and the liner and between the wedging surfaces to ordinarily maintain the liner in operating position intermediate of the journal box and the adjacent wheel, but as additional security in this 25 respect a set screw M is provided, the same having threaded engagement with one of the flanges G of the liner so as to be carried 30 by the latter and be adapted to screw into a recess m in the side of the journal box to interlock the parts together.

While we have herein illustrated a particular embodiment of the invention, it will 35 be understood by persons skilled in the art to which the invention pertains that changes in the illustrated construction or other embodiments may be resorted to, as may be in keeping with the hereto appended claims.

- 40 Having thus described the invention, what is claimed is:

1. The combination with a journal box, of a liner therefor, said journal box and lining having coöperating means for securing the liner to the journal box including 45 parts acting to draw the liner toward and into impinging relation to the adjacent face of the end of the journal box.

2. The combination with a journal box, 50 of a liner therefor, said journal box and lining having coöperating means for securing the liner to the journal box including parts acting to draw the liner toward and into impinging relation to the adjacent face 55 of the end of the journal box, the contacting

surfaces of the liner and journal box being of an area substantially co-extensive with the size of the liner.

3. The combination with a journal box, 60 of a liner having its inner face formed to contact with the adjacent end of the journal box, said journal box and lining having co-operating means for securing the liner against the face of said end including wedging parts at the sides of the journal box receding outwardly toward the bottom of the 65 box to incline away from said face, and co-operating edges on the liner.

4. The combination with a journal box, 70 of a liner therefor, said journal box and lining having coöperating means for securing the liner to the journal box including parts acting to draw the liner into impinging relation to the adjacent end of the journal box, the contacting surfaces of the liner 75 and journal box being of an area substantially co-extensive with the size of the liner, those portions of the sides of the journal box and edges of the liner opposite the wedging surfaces being removed with reference to each other to prevent engagement therebetween, substantially as described.

5. The combination with a journal box, 80 of a liner for one end of the same, said journal box and liner having coöperating wedge parts for securing the liner to the journal box, said wedge parts being located at the sides of the journal box and adjacent side edges of the liner and acting to draw the liner toward the face of the end of the box. 85

6. The combination with a journal box, 90 of a liner for one end of the same, said journal box and liner having coöperating wedge parts for securing the liner to the journal box, said wedge parts being located at the 95 sides of the journal box and adjacent side edges of the liner and acting to draw the liner toward the face of the end of the box, and interlocking means between one of the edge portions of the liner and the adjacent 100 side of the journal box.

In testimony whereof we hereunto affix our signatures in the presence of two witnesses.

WILLIAM K. LYNN.
WALTER T. WEAVER.
